Leopold H. Sterne, New York, N. Y., and Winfred N. Lurcott, Elizabeth, N. J.; said Lurcott assignor to said Sterne

Application November 18, 1941, Serial No. 419,536

18 Claims. (Cl. 51—122)

This invention relates to machines of the type covered by U. S. Patent to Joseph G. C. Mantle, No. 1,313,402 for grinding and polishing gems, such as diamonds and other bodies requiring similar operations. The invention will be illustrated and described in connection with a machine more particularly designed for the grinding and polishing of diamonds on a rotary lap.

Among the objects of the present invention are improved and simplified mechanism for feeding the diamond to the rotary lap and automatically withdrawing the diamond therefrom after the diamond has been ground or polished to a predetermined extent, improved and simplified mechanism for locating the diamond at different radial positions on the surface of the rotary lap and also improved and simplified mechanism for effecting reciprocation of the diamond radially of the rotary lap during the grinding or polishing operation.

Other objects, novel features and advantages of this invention will become apparent from the following specification and accompanying drawings, wherein:

Fig. 1 is a front elevation of a device embodying the invention;

Fig. 2 is a side elevation;

Fig. 3 is a section on the line 3—3 of Fig. 1;

Fig. 4 is a section on the line 4—4 of Fig. 5;

Fig. 5 is a fragmentary section on the line 5—5 of Fig. 6;

Fig. 6 is a section on the line 6—6 of Fig. 1;

Fig. 7 is a section on the line 7—7 of Fig. 2;

Figs. 8 and 9 are views similar to Fig. 7 in different positions of operation;

Fig. 10 is a section on the line 10—10 of Fig. 9;

Fig. 11 is a perspective view of a portion of the apparatus;

Fig. 12 is a fragmentary detail view, and

Fig. 13 is a view similar to Fig. 7 of a modification.

A grinding wheel or rotary lap 10 is carried by a vertical shaft 11 mounted in suitable bearings (not shown) and driven by any suitable source of power. A table or bench 12 has a substantially circular recess in which the wheel 10 is located.

A main frame 13 is mounted on the bench 12 and is provided with pivot pins 14 and 15, the pin 15 being adjustable toward and away from the pin 14 by reason of being screw-threaded into the frame. A lock nut 16 is provided on the pin 15 for holding the pin 15 in any position of adjustment.

A frame piece 17 is journaled in the main

frame by means of the pivot pins 14 and 15 for oscillation about a horizontal axis parallel to the plane of the grinding wheel 10. A lever 18 having a handle 19 is pivoted on an upright projection 20 on the frame piece 17. The lever 18 is adapted to engage a short lever 21 on a rocking shaft 22 journaled in the upright projection 20. At the remaining end of the rocking shaft 22 is provided a short lever 23 adapted to engage a pin 24 slidably mounted through the frame piece 17 and having its lower end adapted to engage the outer end of a lever 25. A spring-pressed plunger 26 in the main frame 13 normally presses the lever 25 upwardly. The lever 25 is pivoted to the main frame at 27 and is provided with a hooked end 28 adapted to engage the ends of a lug 29 when normally pressed upwardly by the plunger 26, the lug 29 being integral with the frame piece 17 so that when the hooked end 28 engages the lug 29, it is impossible to rotate the frame piece 17 upwardly, the same being locked by the engagement of the hooked end 28 with the lug 29. However, when the handle is thrown clockwise, it acts upon the lever 21 of the rocker shaft 22 to cause the lever 23 to press the pin 24 downward, which forces the lever 25 out of engagement with the lug 29 and theretupon further movement of the handle 19 in clockwise direction, as viewed in Fig. 2, causes the frame piece 17 to be rotated in clockwise direction. This movement may be continued until the other end of the lug 29 abuts the outer portion of the hooked end 28 of the lever 25, whereupon the parts will be maintained in the position just described. A reverse movement of the handle 18 will bring the parts back into the position shown in Fig. 2.

The frame piece 17 is provided with a dovetail guide member 30 provided with a longitudinal groove. In this groove is slidably mounted a member 31 having a central bore in which is arranged a feed screw 32 at one end of which is provided an exposed hexagonal head 33 by means of which rotation of the feed screw is effected through use of a suitable tool having a socket to receive the head 33. The member 31 carries a lug 34 having an aperture in which is received the pivot pin 14. In the periphery of the lug 34 is provided a slot 35 transverse of the member 31 and in this slot is received a pin 36 located at the upper end of a vertical shaft 37 in offset relation to the axis of the shaft. At the lower end of the shaft 37 is a worm wheel 38 which meshes with a worm 39 at the end of a horizontal shaft 40 supported by the main

frame. The shaft 40 is connected by a suitable coupling 41 to the armature shaft of a motor 42 mounted in the main frame. Rotation of the shaft 37 by the motor 42 causes horizontal reciprocation of the member 31.

A casing 43 is provided with guideways 44 in which the guide member 30 is arranged. A lug 45 projects from the casing 43 through a slot 46 into the interior of the member 31 and is provided with a screw-threaded bore receiving the feed screw 32. The arrangement is such that rotation of the feed screw 32 effects horizontal adjustment of the casing 43 relative to the axis of the grinding wheel 10.

The casing 43 is provided with a removable cover 47. The casing is provided with an extension 48 having a vertical passageway 49 which communicates with the interior of the casing over a portion of its length as shown in Figs. 7 to 9 inclusive. A tube 50 is slidably mounted in the casing and is held against rotary movement by a key 51 supported by the projection 48 and extending through the slot 52 in the tube. A rod 53 is slidably mounted in the tube 50 and is held against rotational movement by the key 51 which projects into the slot 54 in the rod. The rod 53 is of less length than the tube 50 and is provided with a central bore terminating short of its lower end, such bore comprising three portions 55, 56 and 57 of different diameter. An adjustment screw 58 is threaded into the upper end of the bore portion 55 with the under surface of its head 58a contacting the upper end of the tube 50. The bore portion 56 contains a helical spring 59, one end of which engages the lower end of the bore portion 56 and the other end of which engages the head 60a of a rod 60 extending through the bore portions 56 and 57. In the lower end of the tube 50 is arranged a plug 61 which is rotatable in the tube and through which the rod 60 extends. The lower end of the plug 61 is provided with a recess receiving a nut 62 screwed on to the end of the rod 60 and serving to hold the rod 53 and the plug 61 in assembled relation to the tube 50. The spring 59 tends to draw the rod 53 downwardly so that the under surface of the head 58a is at all times maintained in contact with the top end of the tube 50 irrespective of the vertical adjustment of the head relative to the rod 53.

A pair of levers 64 and 65 are mounted on pivot pins 66 and 67 in the casing 43, the pivot pins being arranged adjacent the bore 49 and being in substantial vertical alinement. The left end of each of the levers 64 and 65 extends into a recess 68 in the rod 53. Also supported by the pivot pin 67 is a lever 70 consisting of two plates 71 arranged at opposite sides of the lever 65 and being interjoined by a cross bar 72. An arm 73 is pivotally supported from the wall of the casing 43 near the bottom thereof and is provided with an adjustment member 74 for regulating the height of the free end of the arm 73 above the bottom of the casing. The arm 73 supports a helical spring 75 on the top of which is arranged a cap 76 having extensions 77 projecting upwardly with each extension being connected to one plate 71. The spring 75 tends to oppose downward movement of the lever 70 from a position of rest and restore said lever to its position of rest after being moved downward.

A bell crank lever 78 is pivotally supported by a pin 79 extending between the arms 71 with a long arm extending substantially horizontally and a short arm extending substantially verti-

cally. The end of the vertical arm is provided with a hook 80 and a pin 81 underlies the long arm to limit downward movement thereof. A lever 82 is pivotally supported by a pin 83 extending between the plates 71 of the lever 70 and has a reverse bend to the left of the pivot pin for the purpose of establishing one end of the lever below the left end of the bell crank lever 78 in one position of the two levers. A pin 84 is provided to limit clockwise rotation of the lever 82. The right end of the lever 82 pivotally supports an arm 85, the lower end of which is provided with a shoulder 86 adapted for engagement with a stop 87 extending between the plates 71. The upper end of the arm 85 is adapted to project into the path of a pin 88 carried by a gear wheel 89 mounted on a shaft 90 journalled in the casing 43.

The shaft 90 also is provided with a pinion 91 which meshes with a gear 92 mounted on a shaft 93 journalled in the casing 43. The shaft 93 also is provided with a pinion 94 which meshes with a gear segment 95 at the right end of the lever 64. A spring 96 on the shaft 90 tends to effect clockwise rotation of the wheel 89 to a position of rest upon counter-clockwise movement of the wheel from such position. The shaft 90 extends through the cover 47 and is equipped at its end with a pointer 97 and on the cover 47 is a dial 98 provided with indicia representing thousandths of an inch. The gear 89 meshes with a pinion 99 supported by a shaft 100 journalled in the casing 43 and arm 101 is pivoted centrally to the shaft 100 by pin 101a. A cylinder 102 is provided within the casing coaxial with the shaft 100. The arm 101 is greater in length than the interior diameter of the cylinder 102 and is tilted so that one end extends into the cylinder. The arrangement of the arm 101 is such that rotation of the shaft 100 tends to arrange the arm 101 perpendicular to the axis of the shaft under centrifugal force, thereby forcing one end of the arm into contact with the inner surface of the cylinder 102 to act as a brake and limit the rotational speed of the shaft 100.

When, as will later be explained, the lever 70 is in the position shown in Fig. 8, the spring 75 exerts a force on the bar 53 tending to effect downward movement of the tube 50. Also, when as will later be explained, the lever 64 is in the position shown in Fig. 9, the spring 96 exerts a force on the bar 53 tending to effect upward movement thereof. The relation of the strengths of the springs 75 and 96 is such that the downward force applied to the bar is greater than the upward force so that when both forces are applied, the resulting movement of the tube is downward. The strength of the spring 96 is sufficient to effect upward movement of the tube 50 from the position shown in Fig. 9 when the force of the spring 75 is not applied to the lever 65.

A guide member 103 is mounted in the casing 43 in position to be engaged by the hook 80 and the lower end of the arm 85 upon clockwise rotation of the lever 70. Also, at the outer end of the lever 65 is provided a pivoted latch 104 for engagement by the hook 80 to interconnect the levers 65 and 70. The latch 104 is provided with a slot 104a into which projects a pin 104b carried by the lever 65. The latch 104 is normally held in the position shown in Fig. 12 by gravity and further counterclockwise rotation of the latch is prevented by the pin and slot arrangement.

A shaft 105 is journalled in the wall of the casing and is provided with a handle 106 in the form of a yoke with the yoke preferably being offset relative to the axis of the shaft. A feed screw 107 is journalled in the yoke and on the feed screw 107 is arranged a weight 108 having a sliding connection with the yoke. The inner end of the shaft 105 has a crank arm 109 at the end of which is provided a pin 110. A block 111 is rotatably supported by the pin 109 and is received in a slot 112 in the cross member 12 of the lever 70. Rotation of the shaft 105 therefore is effective to actuate the lever 70.

A diamond holder 113 preferably of the structure shown in Patent No. 1,313,402 is carried by the plug 61.

Fig. 7 illustrates the arrangement of the various parts prior to the beginning of a grinding operation. With the parts in this position, the handle 106 is in horizontal position with the weight 108 opposing movement thereof from such position. The gear wheel 89 is in such position that the dial indicates the maximum reading. The levers 65 and 70 are disconnected while the lever 82 is at the limit of its clockwise movement and the lever 78 is at the limit of its counter-clockwise movement. In order to bring the diamond into operative relation to the grinding wheel, the handle 106 is rotated into vertical position shown in Fig. 2, thereby causing downward movement of the lever 70 into the position shown in Fig. 8, such downward movement being effected through the medium of the shaft 105, crank arm 109, pin 110, block 111 and cross-bar 72. Such downward movement compresses the spring 75 and the hook 80 is directed by the guide 103 into engagement with the latch 104 with consequent clockwise rotation of the latch 104 to permit the hook 80 to underlie the bottom edge of the latch whereupon the latch assumes the position shown in Fig. 12 and in Fig. 8, thereby interconnecting the levers 65 and 70. Concurrently, the left end of the lever 78 is lifted away from the pin 81. Following such action, the arm 85 is lifted relative to the lever 70 and slightly rotated by engagement with the guide 103 to cause the shoulder 86 to engage with the stop 87 and to swing the lever 82 counterclockwise to locate the left end thereof under the left end of the lever 78, thereby locking the hook 80 in engagement with the latch 104. Upon release of the handle 106, the levers 71 and 65 move upwardly under the influence of the spring 75 and counter-clockwise movement of the lever 75 causes downward movement of the rod 53 which in turn causes counter-clockwise rotation of the lever 64. Such movement of the lever 64 results in clockwise rotation of the gear wheel 89, the rotational speed of which is controlled by the brake arm 101 and in placing the spring 96 under tension. The upward movement of the lever 70 also locates the upper end of the arm 85 in the path of the pin 88. Downward movement of the bar 53 is communicated to the diamond holder 113 through the head 58a of the screw 58, the tube 50 and the plug 61, and is continued until the pin 88 engages the top end of the arm 85, whereupon the latter is rocked to disengage the shoulder 86 from the detent 87, thereby allowing the lever 88 to swing clockwise under the influence of gravity to release the bell crank lever 78 which swings counter-clockwise to release the lever 65. The spring 75 no longer exerts a downward force on the rod 53 through 75

the lever 65 and the spring 96 now becomes effective to cause clockwise rotation of the lever 64 to lift the bar 53 and tube 50 to move the diamond away from the wheel. The position of the pin 88 when the diamond engages the wheel is regulated by the screw 58 which adjusts the position of the bar 53 in the tube 50. Adjustment of the rod 53 in the tube 50 may be effected either before or after the diamond is brought into engagement with the grinding wheel and the adjustment is made such that the pin 88 will engage the arm 85 when the diamond has been ground to a desired extent.

The correct adjustment of the rod 53 to effect the desired extent of grinding is determined by reference to the dial 98. This dial is suitably calibrated that with the diamond engaging the wheel 10, the reading of the dial at the pointer 97 gives the number of thousandths of an inch that the diamond must be ground to bring the pin 88 into tripping relation to the arm 85.

In the modification illustrated in Fig. 13, a different form of interconnection is provided between the levers 65 and 70. A latch 114 is pivoted to the lever 65 and a spring 115 tends to rotate the latch counter-clockwise. At the upper end of the latch 114 is a hook which is adapted to engage a shoulder 116 formed on the lever 70. The latch 114 is disengaged from the shoulder 116 by electromagnetic means. A solenoid 117 has an armature 118 which, when the levers 65 and 70 are in the position shown in Fig. 13 (corresponding to the position shown in Fig. 9) has its lower end engaging the left side of the latch 114. In series with the solenoid winding is a pair of contacts 119 which are spring-biased away from each other so that the solenoid circuit is normally open. One contact 119 is carried by a resilient arm 120 extending into the path of the pin 88 of the gear wheel 89. The pin is effective to move the arm 120 to close the contacts 119, thereby energizing the solenoid to pull the armature 118 rightward thereby disengaging the latch 114 from the shoulder 116 to disconnect the arm 65 from the arm 70 as previously described in connection with the modification illustrated in Fig. 7.

The wheel 10 is provided with several concentric bands of different coarseness abrasive, the outer band usually being the coarsest and the abrasive becoming progressively less coarse in the bands nearer the center of the wheel. The diamond is brought into grinding relation with the several abrasive bands by rotation of the feed screw 32 to adjust the casing 43 radially of the grinding wheel.

During the grinding operation, the diamond is caused to move back and forth across an abrasive band by reciprocation of the member 31. Such reciprocation is effected through the medium of the pin 36 which is moved in a circular orbit by the shaft 37 by the motor 42 and extends into the slot 35.

The diamond may be swung up away from the grinding wheel for inspection purposes without in any way changing any of the adjustments. Such swinging of the diamond is accomplished by operation of the handle 19 in the manner previously described to rotate the frame piece 17. The frame piece carries with it the casing 33 and the various parts supported thereby and the pin 36 remains projected into the slot 35.

We claim:

1. In an apparatus of the character described,

a casing, a member slidably supported by said casing, a first and a second lever pivoted in said casing, interconnections between one end of each lever and said member, means applying force to said first lever tending to move said member in one direction, means applying a greater force to said second lever tending to move said member in the opposite direction, and means actuatable upon a predetermined extent of movement of said first lever to render inoperative said greater force-applying means. 10

2. In an apparatus of the character described, a casing, a first member slidably supported by said casing, a second member adjustably attached to said first member, a first and a second lever pivoted in said casing, interconnections between one end of each lever and said second member, means applying force to said first lever tending to move said first member in one direction, means applying a greater force to said second lever tending to move said first member in the opposite direction, means actuatable upon a predetermined extent of movement of said first lever to render inoperative said greater force-applying means. 15

3. In an apparatus of the character described, a casing, a member slidably supported by said casing, a first lever pivoted in said casing, a second and a third lever coaxially pivoted in said casing, interconnections between one end of each of the first and second levers and said member, a releasable interconnection between said second and third levers for unitary movement, means applying force to said first lever tending to move said member in one direction, means applying a greater force to said third lever tending to move said member in the opposite direction, and means actuatable upon a predetermined extent of movement of said first lever to release the interconnection between said second and third levers. 20

4. In an apparatus of the character described, a casing, a first member slidably supported by said casing, a second member adjustably attached to said first member, a first lever pivoted in said casing, a second and a third lever coaxially pivoted in said casing, a releasable interconnection between said second lever and said third lever for effecting unitary movement thereof, means applying force to said first lever tending to move said first member in one direction, means applying a greater force to said third lever tending to move said first member in the opposite direction, and means actuatable upon a predetermined extent of movement of said first lever to release the interconnection between said second and third levers. 25

5. In an apparatus of the character described, a casing, a tube slidably supported by said casing and having a longitudinal slot, a first and a second lever pivoted in said casing with one end of each lever extending into said slot, interconnection between said lever ends and said tube, means applying force to said first lever tending to move said tube in one direction, means applying a greater force to said second lever tending to move said tube in the opposite direction, and means actuatable upon a predetermined extent of movement of said first lever to render inoperative said greater force-applying means. 30

6. In an apparatus of the character described, a casing, a tube slidably supported by said casing and having a longitudinal slot, a member within said tube adjustably attached thereto and having a recess in alignment with said slot, a first and a second lever pivoted in said casing with one end of each lever extending into said slot, interconnection between said lever ends and said tube, means applying force to said first lever tending to move said tube in one direction, means applying a greater force to said second lever tending to move said tube in the opposite direction, and means actuatable upon a predetermined extent of movement of said first lever to render inoperative said greater force-applying means. 35

one end of each lever projecting through said tube slot into said member recess, means applying force to said first lever tending to move said member in one direction, means applying a greater force to said second lever tending to move said member in the opposite direction, and means actuatable upon a predetermined extent of movement of said first lever to render inoperative said greater force-applying means. 40

7. In an apparatus of the character described, a casing, a tube slidably supported by said casing and having a longitudinal slot, a first lever pivoted in said casing, a second and a third lever coaxially pivoted in said casing, said first and second levers each having one end projecting into said tube through said slot, interconnections therebetween with said tube, a releasable interconnection between said second and third levers, means applying force to said first lever tending to move said tube in one direction, means applying a lesser force to said third lever tending to move said tube in the opposite direction, and means actuatable upon a predetermined extent of movement of said first lever to release the interconnection between said second and third levers. 45

8. In an apparatus of the character described, a casing, a tube slidably supported by said casing and having a longitudinal slot, a member within said tube adjustably attached thereto and having a recess in alignment with the tube slot, a first lever pivoted in said casing, a second and a third lever coaxially pivoted in said casing, said first and second levers each having one end extending through said tube slot into said member recess, a releasable interconnection between said second and third levers for effecting unitary movement thereof, means applying force to said first lever tending to move said member in one direction, means applying a greater force to said third lever tending to move said member in the opposite direction, and means actuatable upon a predetermined extent of movement of said first lever to release the interconnection between said second and third levers. 50

9. In an apparatus of the character described, a casing, a member slidably supported by said casing, a first and a second lever pivoted in said casing, interconnections between one end of each lever and said member, a rotatable member, driving connections between said first lever and said rotatable member, means applying force to said first lever tending to move said slidably member in one direction, means applying greater force to said second lever tending to move said slidably member in the opposite direction, and means actuatable by a predetermined extent of movement of said rotatable member to render inoperative said greater force-applying means. 55

10. In an apparatus of the character described, a casing, a member slidably supported by said casing, a first lever pivoted in said casing, a second and a third lever coaxially pivoted in said casing, means including a pivoted arm releasably interconnecting said second and third levers for unitary movement, interconnections between said slidably member and one end of each of said first and second levers, means applying force to said first lever tending to move said slidably member in one direction, means applying a greater force to said third lever tending to move said slidably member in the opposite direction, a rotatable member, driving connections between said rotatable member and said first lever, and a pin on said rotatable member engageable with said arm. 60

on a predetermined extent of movement of said rotatable member to release the interconnection between said second and third levers.

11. In the apparatus according to claim 3, means including a handle exterior of the casing for effecting movement of said third lever in opposition to said greater force-applying means, and means for effecting automatic interconnection of said second and third levers upon such movement of said third lever.

12. In the apparatus according to claim 4, means including a handle exterior of the casing for effecting movement of said third lever in opposition to said greater force-applying means, and means for effecting automatic interconnection of said second and third levers upon such movement of said third lever.

13. In the apparatus according to claim 7, means including a handle exterior of the casing for effecting movement of said third lever in opposition to said greater force-applying means, and means for effecting automatic interconnection of said second and third levers upon such movement of said third lever.

14. In the apparatus according to claim 8, means including a handle exterior of the casing for effecting movement of said third lever in opposition to said greater force-applying means, and means for effecting automatic interconnection of said second and third levers upon such movement of said third lever.

15. In the apparatus according to claim 10, means including a handle exterior of the casing for effecting movement of said third lever in opposition to said greater force-applying means, and means for effecting automatic interconnection of said second and third levers upon such movement of said third lever.

16. In an apparatus of the character described, a rotatable wheel, a frame overlying said wheel, pivot pins supported by said frame, a frame piece rotatably supported by said pivot pins, a member

slidably supported by said frame piece for reciprocation radially of said wheel, a lug carried by said member and having an aperture receiving one pivot pin and having a slot transverse to said pin axis, a rotatable shaft having at one end an eccentric pin projecting into said slot, driving means for said shaft, and a diamond carrier supported by said member.

17. In an apparatus of the character described, 10 a rotatable wheel, a frame overlying said wheel, pivot pins supported by said frame, a frame piece rotatably supported by said pivot pins, a member 15 slidably supported by said frame piece for reciprocation radially of said wheel, a lug carried by 20 said member and having an aperture receiving one pivot pin and having a slot transverse to said pin axis, a rotatable shaft having at one end an eccentric pin projecting into said slot, driving 25 means for said shaft, a diamond carrier slidably supported by said member and including an interiorly threaded projection, and a feed screw rotatably supported by said member in operative engagement with said projection, said feed screw having an exposed portion for effecting rotation 30 thereof.

18. In an apparatus of the character described, a rotatable wheel, a frame overlying said wheel, pivot pins supported by said frame, a frame piece rotatably supported by said pivot pins, a member 30 slidably supported by said frame piece for reciprocation radially of said wheel, a lug carried by said member and having an aperture receiving one pivot pin, means to effect reciprocation of said member, a diamond carrier slidably supported by said member and including an interiorly 35 threaded projection, and a feed screw rotatably supported by said member in operative engagement with said projection, said feed screw having an exposed portion for effecting rotation thereof.

40

LEOPOLD H. STERNE,
WINFRED N. LURCOTT.
